[57] CLAIM

The ornamental design for an equipment housing module with dual displays, as shown and described.

DESCRIPTION

FIG. 1 is a top, front, and right side perspective view of an equipment housing module with dual displays showing our new design, the broken lines being shown for illustrative purposes;

FIG. 2 is a top, rear, and right side perspective view thereof;

FIG. 3 is a left side elevational view thereof;

FIG. 4 is a bottom plan view thereof.

Fig. 1Fig. 2
